UNITED STATES PATENT OFFICE.

BEN CLIFFORD BLACKMON, OF DALLAS, TEXAS.

MATRIX-MAKING MACHINE.

Application filed October 12, 1925. Serial No. 62,038.

The present invention relates to a machine for assisting a workman in the construction of matrices used in newspapers. A matrix consists of a heavy base, two thinner pieces or sheets, and three sheets of tissue, pasted together. One man, in the ordinary method of making matrices stands at each end of a small table. One man arranges the sheets while the other spreads 10 the paste between the sheets and rolls out each sheet as it is applied to the base sheet. The principal object of the present invention is to do away with the man now necessary to arrange the sheets and to allow one man 15 to make a matrix in less time than by the ordinary method outlined above.

Another important object of the invention is the construction of a machine of this nature so that the same will be exceedingly 20 simple, strong, durable, easy to manipulate, efficient and reliable in its operation, and otherwise well adapted to the purpose for which it is designed.

With the above and numerous other objects in view as will appear as the description proceeds, the invention resides in certain novel features of construction, and in the combination and arrangement of parts 25 as will be hereinafter more fully described 30 and claimed.

In the drawing:—

Figure 1 is a top plan view of the machine embodying the features of my invention.

Figure 2 is a side elevation thereof.

Figure 3 is a front elevation thereof, and

Figure 4 is an enlarged detail vertical section through the forward portion of the movable truck.

Referring to the drawing in detail it will 40 be seen that numerals 5 designate the four legs of the machine which are preferably mounted on casters 6, and are braced by a rectangular frame 7, or in any other suitable manner. A frame 8 is supported at the 45 upper ends of the legs 5 and has mounted thereon a sheet metal top 9. A pair of inclined arms 10 project forwardly from the frame 8 below the top 9, for the purpose of supporting a roller 11 in a handy position as 50 will be more apparent as the description proceeds. A pair of beams 12 are attached to the legs 5 and extend rearwardly therefrom and are inclined upwardly. Tracks 13 are mounted on the upper edges of these

beams 12. One beam is located to each side 55 of the machine. Stops 14 are attached to the beams 12 and extend above the tracks 13 between the legs 5, as is shown to advantage in Figure 2. A pair of posts 15 rise from the beams 12 to the rear of the 60 rear legs 5, and support at their upper ends a shelf 16 which is inclined forwardly and downwardly. A truck 17 is supported on legs 18 and 19. The legs 18 are at the rear 65 of the truck and are slightly longer than the legs 19 so that the truck 17 is inclined forwardly and downwardly. Grooved wheels 20 are journaled at the lower ends of the legs 18 and 19 for riding on the tracks 13. A back 21 rises from the rear edge of the 70 truck 17 and brackets 22 project forwardly therefrom for receiving screws 24 for clamping plate 25 on the truck 17. Brackets 26 project forwardly from the truck and have journaled therebetween a roller 27. Frames 28 rise from the forward end of the truck 17 and slidably support journal blocks 29 in which is journaled a roller 30. Brackets 31 are disposed forwardly of the front legs 19, and rise above the plate 9. A catch 33 is 80 pivoted as at 34 to one beam 12, and is adapted to engage one of the forward legs 19 for holding the truck in its rearward position as shown in Figure 2. A link 35 is pivotally engaged with the catch 33 and with a treadle 85 36 pivoted in the frame 7. When the operator steps on the treadle 36, the catch 33 is released, thereby allowing the truck to roll forwardly on the inclined tracks 13 until the front rollers 20 engage the stops 90 14. A shelf 37 extends from the right hand side of the machine and is adapted to support a paste pot 38. A drain lip 39 inclines downwardly from the right hand edge of the top 9 over the pot 38.

In using the machine, only one worker is required. The heavy base sheets are laid out on the shelf 16 at the top of the machine. The thin sheets are placed on the truck 17. One of the heavy base sheets is taken from the shelf 16 by the workman and placed on the top 9. The paste is applied to this sheet. The treadle 36 is then operated for releasing the truck 17 which moves forwardly. The operator then removes one of the thin sheets from the truck between the rollers 30 and 27, and places the forward edge thereof evenly with the forward edge of the pasted

base sheets. The roller 11 is then brought into play being lifted from the arms 10 and rolled rearwardly. As this roller moves rearwardly it engages the bracket 31 and 5 pushes the truck 17 to its rear position, the catch 31 engaging it in this rear position as is obvious. The second thin sheet is placed on the first thin sheet in a similar manner as will be obvious. The workman then 10 moves the remaining thin sheets from the truck and places in place of them the tissue sheets, and these tissue sheets are applied by the same operations as described incident to the thin sheets. By actual experience it has 15 been found that one man can make the matrices with this machine much more rapidly and efficiently than can two workmen using the ordinary method mentioned above.

It is thought that the construction, operation, and advantages of the invention will 20 now be apparent without a more detailed description thereof. The present embodiment of the invention has been disclosed merely by way of example since in actual practice 25 it attains the features of advantage enumerated as desirable in the statement of the invention and the above description. It will be apparent that this embodiment of the invention possesses superior compactness and 30 convenience both from the standpoint of structure and operation. It will be apparent that numerous changes in the details of construction, and in the combination and arrangement of parts may be resorted to 35 without departing from the spirit or scope of the invention as hereinafter claimed or sacrificing any of its advantages.

Having thus described the invention, what I claim is:—

- 40 1. In a device for making matrices with a hand roller, a supporting structure, a top on the supporting structure, an inclined track way on the supporting structure, a truck movable on said track way, means for normally holding said truck in its rearmost position, brackets extending from the truck so that it may be pushed to its rearmost position by the hand roller, and a shelf supported above the truck on the supporting structure.
- 45 2. In a device for making matrices with a hand roller, a supporting structure, a top on the supporting structure, a pair of arms projecting forwardly from the supporting structure below the top for holding the hand roller, a pair of tracks extending rearwardly and inclined upwardly from the supporting structure, one track on each side thereof below the top, a truck movable on said tracks, a catch pivoted on the supporting structure, means for operating the catch, said catch normally engaging the truck to hold it in its rearmost position so that when said catch is released, the truck will roll forwardly by gravity, and a shelf supported on the supporting structure above the truck, and stops on the tracks below the top to limit the forward movement of the truck.
- 50 3. In a device for making matrices with a hand roller, a supporting structure, a top on the supporting structure, a pair of arms projecting forwardly from the supporting structure below the top for holding the hand roller, a pair of tracks extending rearwardly and inclined upwardly from the supporting structure, one track on each side thereof below the top, a truck movable on said tracks, a catch pivoted on the supporting structure, means for operating the catch, said catch normally engaging the truck to hold it in its rearmost position so that when said catch is released, the truck will roll forwardly by gravity, a shelf supported on the supporting structure above the truck, and stops on the tracks below the top to limit the forward movement of the truck.
- 55 4. In a device for making matrices with a hand roller, a supporting structure, a top on the supporting structure, a pair of arms projecting forwardly from the supporting structure below the top for holding the hand roller, a pair of tracks extending rearwardly and inclined upwardly from the supporting structure, one track on each side thereof below the top, a truck movable on said tracks, a catch pivoted on the supporting structure, means for operating the catch, said catch normally engaging the truck to hold it in its rearmost position so that when said catch is released, the truck will roll forwardly by gravity, and a shelf supported on the supporting structure above the truck, stops on the tracks below the top to limit the forward movement of the truck, brackets extending forwardly from the truck and adapted to be engaged by said roller when the same is brought into operation for pushing the truck to its rearmost position to be caught by the catch.
- 60 5. In a device for making matrices with a hand roller, four upright legs, a frame bracing the lower ends of said legs, a frame bracing the upper ends of said legs, a top on said upper frame, arms extending forwardly from said upper frame and inclined upwardly for holding the roller, a pair of beams, one attached to the legs on each side of the machine, said beams extending rearwardly and upwardly from said legs, tracks on said beams, stops extending upwardly from said beams between the legs, a truck, supporting legs depending from the truck, rollers on the last mentioned supporting legs for movement on said tracks, posts extending upwardly from the intermediate portions of said beams rearwardly of the legs, an inclined shelf on the upper ends of said posts, a catch pivotally mounted on one of the beams for engaging one of the forward legs of the truck, a treadle pivotally mounted between the lower frame, a link between the treadle and the catch, brackets extending forwardly from the forward legs of the truck.

3. In a device for making matrices with a hand roller, a supporting structure, a top on the supporting structure, a pair of arms projecting forwardly from the supporting structure below the top for holding the hand roller, a pair of tracks extending rearwardly and inclined upwardly from the supporting structure, one track on each side thereof below the top, a truck movable on said tracks, a catch pivoted on the supporting structure, means for operating the catch, said catch normally engaging the truck to hold it in its rearmost position so that when said catch is released, the truck will roll forwardly by gravity, a shelf supported on the supporting structure above the truck, and stops on the tracks below the top to limit the forward movement of the truck.

4. In a device for making matrices with a hand roller, a supporting structure, a top on the supporting structure, a pair of arms projecting forwardly from the supporting structure below the top for holding the hand roller, a pair of tracks extending rearwardly and inclined upwardly from the supporting structure, one track on each side thereof below the top, a truck movable on said tracks, a catch pivoted on the supporting structure, means for operating the catch, said catch normally engaging the truck to hold it in its rearmost position so that when said catch is released, the truck will roll forwardly by gravity, and a shelf supported on the supporting structure above the truck, stops on the tracks below the top to limit the forward movement of the truck, brackets extending forwardly from the truck and adapted to be engaged by said roller when the same is brought into operation for pushing the truck to its rearmost position to be caught by the catch.

5. In a device for making matrices with a hand roller, four upright legs, a frame bracing the lower ends of said legs, a frame bracing the upper ends of said legs, a top on said upper frame, arms extending forwardly from said upper frame and inclined upwardly for holding the roller, a pair of beams, one attached to the legs on each side of the machine, said beams extending rearwardly and upwardly from said legs, tracks on said beams, stops extending upwardly from said beams between the legs, a truck, supporting legs depending from the truck, rollers on the last mentioned supporting legs for movement on said tracks, posts extending upwardly from the intermediate portions of said beams rearwardly of the legs, an inclined shelf on the upper ends of said posts, a catch pivotally mounted on one of the beams for engaging one of the forward legs of the truck, a treadle pivotally mounted between the lower frame, a link between the treadle and the catch, brackets extending forwardly from the forward legs of the truck.

adapted to be engaged by the first mentioned roller so that the truck may be moved rearwardly thereby.

6. In a device for making matrices with a hand roller, four upright legs, a frame bracing the lower ends of said legs, a frame bracing the upper ends of said legs, a top on said upper frame, arms extending forwardly from said upper frame and inclined upwardly for holding the roller, a pair of beams, one attached to the legs on each side of the machine, said beams extending rearwardly and upwardly from said legs, tracks on said beams, stops extending upwardly from said beams between the legs, a truck, supporting legs depending from the truck, rollers on the last mentioned supporting legs for movement on said tracks, posts extending upwardly from the intermediate portion of said beams rearwardly of the legs, an inclined shelf on the upper ends of said posts, a catch pivotally mounted on one of the beams for engaging one of the forward legs of the truck, a treadle pivotally mounted between the lower frame, a link between the treadle and the catch, brackets extending forwardly from the forward legs of the truck adapted to be engaged by the first mentioned roller so that the truck may be moved rearwardly thereby, frames extending upwardly from the truck at the forward end thereof, blocks slidable in the last mentioned frames, a roller journaled in said blocks.

7. In a device for making matrices with a hand roller, four upright legs, a frame bracing the lower ends of said legs, a frame bracing the upper ends of said legs, a top on said upper frame, arms extending forwardly from said upper frame and inclined upwardly for holding the roller, a pair of beams, one attached to the legs on each side of the machine, said beams extending rearwardly and upwardly from said legs, tracks on said beams, stops extending upwardly from said beams between the legs, a truck, supporting legs depending from the truck, rollers on the last mentioned supporting legs for movement on said tracks, posts extending upwardly from the intermediate portion of said beams rearwardly of the legs, an inclined shelf on the upper ends of said posts, a catch pivotally mounted on one of the beams for engaging one of the forward legs of the truck, a treadle pivotally mounted between the lower frame, a link between the treadle and the catch, brackets extending forwardly from the forward legs of the truck adapted to be engaged by the first mentioned roller so that the truck may be moved rearwardly thereby, frames extending upwardly from the truck at the forward end thereof, blocks slidable in the last mentioned frames, a roller journaled in said blocks, brackets extending

forwardly from the truck, and a roller journaled between said last mentioned brackets.

8. In a device for making matrices with a hand roller, a supporting structure, a top on the supporting structure, an inclined trackway on the supporting structure being inclined upwardly and rearwardly therefrom, a truck movable on said trackway, releasable means for holding said truck in its rearmost position on said trackway, and brackets extending from the truck so that they may be engaged by the hand roller as the latter is rolled over the top to push the truck to its rearmost position on the trackway.

9. In a device for making matrices with a hand roller, a top, an inclined trackway disposed to extend upwardly and rearwardly in relation to the top, a truck movable on said trackway, releasable means for holding said truck in its rearmost position on said trackway, and brackets extending from the truck and adapted to be engaged by the hand roller as the latter is rolled over the top for pushing the truck to its rearmost position on the trackway.

10. In a device for making matrices with a hand roller, an inclined trackway, a truck movable on said trackway, and releasable means for holding said truck in its rearmost position on said trackway.

11. In a device for making matrices with a hand roller, an inclined trackway, a truck movable on said trackway, releasable means for holding said truck in its rearmost position on said trackway, and brackets extending from the trackway for engagement by the hand roller to be pushed rearwardly so as to position the truck in its rearmost position on the trackway.

12. In a device for making matrices with a hand roller, an inclined trackway, a truck movable on the inclined trackway, a releasable catch for holding the truck at the upper end of the trackway, stops at the lower portion of the trackway against which said truck is adapted to engage when the means is released.

13. In a device for making matrices with a hand roller, a trackway, a truck movable on the trackway, frames rising from the truck, journal boxes slidable in the frames, and a roller journaled in the boxes.

14. In a device for making matrices with a hand roller, a trackway, a truck movable on the trackway, frames rising from the truck, journal boxes slidable in the frames, a roller journaled in the boxes, and a second roller journaled at the front edge of the truck adjacent the frame.

In testimony whereof I affix my signature.
BEN CLIFFORD BLACKMON.
